BOTTLE

William C. Harris, Racine County, Wis., assignor to
S. C. Johnson & Son, Inc., Racine, Wis.

Filed Sept. 18, 1964, Ser. No. 81,787

Term of patent 14 years

(Cl. D58—5)

FIG. 1 is a side perspective view of a bottle, showing my new design;

FIG. 2 is a perspective view slightly rotated clockwise from the position in FIG. 1;

FIG. 3 is a perspective from the right of FIG. 1;

FIG. 4 is a perspective from the left of FIG. 1; and

FIG. 5 is a perspective slightly rotated counterclockwise from the position in FIG. 1.

I claim:

The ornamental design for a bottle, substantially as shown.
